CLAIM

The ornamental design for an integration management system for patient table, as shown and described.

DESCRIPTION

FIG. 1 is a front perspective view of an integration management system for patient table;

FIG. 2 is a back perspective view thereof;

FIG. 3 is a top view thereof;

FIG. 4 is a right side view thereof;

FIG. 5 is a left side view thereof;

FIG. 6 is a back view thereof;

FIG. 7 is a front view thereof;

FIG. 8 is a bottom view thereof;

FIG. 9 is a front perspective view thereof with the lower table compartment in an open configuration; and,

FIG. 10 is a back perspective view thereof.

The broken lines immediately adjacent the shaded areas represent the bounds of the claim, while all other broken lines are directed to environment and are for illustrative purposes only. The broken lines form no part of the claimed design.
